UNITED STATES PATENT OFFICE.

ROBERT E. KING, OF BEAUFORT, NORTH CAROLINA.

DRUGGIST'S PRESCRIPTION-FILE.

No. 810,772.

Specification of Letters Patent.

Patented Jan. 23, 1906.

Application filed August 2, 1905. Serial No. 272,406.

To all whom it may concern:

Be it known that I, ROBERT E. KING, a citizen of the United States, residing at Beaufort, in the county of Carteret and State of North Carolina, have invented new and useful Improvements in Druggists' Prescription-Files, of which the following is a specification.

My invention relates to druggists' prescription-files; and its primary object is to provide a novel and highly useful device of this character by means of which prescriptions may be quickly filed numerically for ready reference.

A further object is to provide a prescription-file which is comparatively simple of construction and which may be readily and cheaply manufactured.

With the above and other objects in view the invention consists of the construction, combination, and arrangement of parts hereinafter fully described, claimed, and illustrated in the accompanying drawings, wherein—

Figure 1 is a side elevation of a prescription-file constructed in accordance with my invention. Fig. 2 is a front elevational view thereof. Fig. 3 is a detailed front elevation of a fragmentary portion of one form of belt or apron, and Fig. 4 is a similar view of another form of belt or apron.

Referring to the drawings by reference-numerals, 1 designates a base of an area and construction to best adapt it for the purpose for which it is intended.

2 designates vertical columns, being provided at their lower ends with horizontally-disposed flanges 3, through the medium of which the columns may be secured upon the base 1. The columns 2 are united at their upper ends by means of transverse and longitudinally-extending bars 4 and 5, respectively. The columns 2 are provided with downwardly and inwardly curved slots 6, the same terminating in bearings for the reception of the projecting ends of shafts 7. Drums 8 are keyed to the shafts 7, whereby they are removably mounted for rotary movement. The ends of the shafts 7 are squared, as at 9, whereby to permit of the application of crank-handles 9^a, by means of which the drums are revolved. Through the virtue of the inwardly and downwardly curvature of the slots 6 all liability of the shafts 7 becoming accidentally disengaged from their bearings is obviated. The drums are mounted in pairs, and a belt or apron 10, of a suitable

length and constructed of canvas or other suitable material, has one end secured to one of the drums of each pair and wound thereabout. The opposite or free end of the belt 60 or apron is carried upwardly and secured to the face of the other drum of the pair, whereby the revolution of one drum will wind the belt or apron thereon from off of the other drum. Each belt or apron has secured to its 65 front face along its longitudinal center a tape 11 by means of stitches 12, whereby the tape is secured in position to provide pockets for the reception of one or more prescriptions. If it is found preferable, the belt or apron 10 70 may be provided with a plurality of slits 13 on either side of its longitudinal center, whereby to also provide pockets for the reception of one or more prescriptions.

In practice two pairs of drums 8 are journaled upon the columns 2, and each pair has secured thereto, as above described, a belt or apron 10. The greater portion of the belt or apron 10 is wound around the drum of each pair nearer to the operator, and that portion 75 thereof which extends from the under face of the drum just mentioned over to the drum farther removed from the operator is not provided with pockets, as this portion of the belt or apron cannot be made further use of. As a 80 prescription is filled it is provided with a number and then inserted in one of the pockets. As the pockets are filled the belt or apron 10 is wound on the farther-removed drum of the pair face downward, whereby prescriptions 85 are hidden from view and whereby they may be more readily preserved. After one belt or apron has been used the drum upon which the belt or apron is wound is removed and placed upon a shelf or other support, which 90 shelf or support may be suitably marked to indicate the numbers of the prescriptions upon the drum; after which the remaining drum of the pair is moved into the position which was occupied by the drum just removed and the other drum, provided with an empty belt or apron, is substituted therefor. After this new drum has been inserted in proper position the free end of the belt or apron is secured to the new drum. The carrying capacity of each belt or apron may be increased by inserting in numerical order 95 more than one prescription in each pocket. If it is desired to examine a prescription wound upon one drum of each pair, it is only 100 necessary to turn the other drum of each pair to bring the prescription into view, this being 105 110

only resorted to when each belt or apron has only been partially used.

The upper edges of the longitudinal braces 5 are formed to provide bearings 14, the same 5 being adapted for the reception of the ends of a shaft 7^a, carrying what may be termed an "examining-drum." Projecting from one end of the frame are bracket-arms 16, having their projecting ends curved upwardly and 10 formed to provide bearings 17. The bearings 17 are adapted to receive the ends of a shaft of one of the drums which has been filed away, and the end of the belt or apron carried thereby is secured to the drum 15, and 15 the belt or apron may be wound on the drum 15, whereby to permit of the examination of any prescription on the other drum.

It is apparent from the above description, taken in connection with the accompanying 20 drawings, that I provide a druggist's prescription-file by means of which prescriptions may be filed in numerical order, by means of which the prescriptions may be referred to readily, and that the drums may be easily and 25 quickly removed from the machine to be filed away and as quickly and easily applied thereto. It is further apparent that the provision made for examining those drums filed away, together with the manner in which the pre- 30 scriptions are applied to the belts or aprons, renders it possible to refer quickly to any prescription, no matter how old the same may be. It may be further desirable to use a belt or apron without pockets for the reception 35 of prescriptions, and in this construction of belt or apron the prescriptions may be secured thereto by some adhesive substance.

Changes in the form, proportions, and minor details of construction may be made within the scope of the invention without 40 departing from the spirit or sacrificing any of the advantages thereof.

Having fully described and illustrated my invention, what I claim is—

1. In a device of the character set forth, 45 the combination of a pair of drums revolvably mounted, a belt or apron carried by one of said drums and adapted to be wound therefrom upon the other drum, and a tape secured to said belt or apron so as to provide a 50 pocket for the reception of a prescription.

2. In a device of the character set forth, 55 the combination of a pair of drums revolvably mounted, a belt or apron carried by one of said drums and adapted to be wound therefrom upon the other drum, and a tape positioned longitudinally upon said belt or apron and secured thereto by means of stitches spaced apart to provide a pocket for the 60 reception of a prescription.

3. In a device of the character set forth, 65 the combination of a pair of drums mounted revolvably and movably, and a belt or apron carried by one of said drums and adapted to be wound therefrom upon the other drum, and a tape secured to said belt or apron by means of stitches spaced apart to provide 70 pockets for the reception of prescriptions.

In testimony whereof I affix my signature in presence of two witnesses.

ROBERT E. KING.
